FIXED BEVEL KNIFE CLAMPING BLOCK

Herbert R. Polleys, New Haven, Conn., and George Rae-
burn, Arlington, Mass., assignors to Wellman Com-
pany, Medford, Mass., a corporation of Maine

Filed Apr. 30, 1962, Ser. No. 190,868
2 Claims. (Cl. 12—86.6)

This invention relates to a cutting machine. More par-
ticularly, it relates to an improved knife clamping block
for a sole cutting machine which has a fixed cutting angle.

The machine for which this invention is an improve-
ment is illustrated and described in the patent to Patten
No. 1,418,604.

Heretofore, it has been practice to use an adjustable
angle knife clamping block for holding the knife used to
cut bevel edges on various types of soles. The clamping
block was pivotally secured to a swivel block by a clamping
screw and held at various angles by a second screw
which extended through one face of the swivel block and
exerted a force on one side of the clamping block.

Although it was possible to use a block of this kind
to obtain various angle settings by merely loosening the
set screw and pivoting the block to a new position, it
was found that many problems in accuracy were encoun-
tered. For example, the correct knife blade setting de-
pended entirely upon the skill and ability of a trained
operator to adjust this desired angle. The procedure
utilized in this setting was a clamp and try proposition
and frequently, even after an accurate angle was set, the
set screw loosened and gave undesirable results. Fur-
thermore, the soles had to be test cut and checked which
is a very time-consuming operation, resulting in loss of
machine output.

The present invention relates to a fixed angle knife
clamping block and has as one of its objects a positive
locking element designed to maintain the cutting knife at
a constant angle regardless of the amount of force ex-
erted thereon and regardless of the skill and ability of
the machine operator.

A further object of the invention is to eliminate the
need for test cuts to determine angle accuracy, since it
is impossible to obtain an inaccurate angle setting with
the new and improved fixed angle clamping block.

A still further object is to provide a device which is
simpler to make and which requires fewer parts.

A further object is to provide a block which is easily
installed and therefore easily replaced by an unskilled
operator with a similar block having a different cutting
angle.

These and other objects are accomplished by providing
a clamping block with an element which extends from the
main body thereof and is adapted to engage a portion of
a supporting swivel block. The element is positioned so
as to prevent rotation of said clamping block when force
is exerted on the cutting blade and thereby maintains the
cutting blade at a fixed angle.

Various changes and modifications in detail for the
device may be made within the scope of the invention.

Referring to the drawings:

FIG. 1 is a rear elevational view showing a standard
bifurcated swivel block in combination with the new and
improved fixed angle knife clamping block;

FIG. 2 is a side elevational view of the swivel block

2

and knife clamping block and further illustrating the po-
sition of the clamping block and the possible angle vari-
ations with different blocks.

This invention is intended to be used with a cutting
machine, a portion of which is illustrated in FIGS. 1 and 2.

A knife supporting mechanism is shown generally at 10
in FIG. 1 and is described in the above-mentioned patent
to Patten No. 1,418,604. The mechanism is provided
with downwardly extending spaced arms 11 and 11a be-
tween which is disposed a bifurcated knife clamping block
12, the latter being pivotally held in position by the screw
13 which passes through an aperture 14 in arm 11a and
apertures 15 and 16 in block 12 and is threaded in arm
11 through thread aperture 17.

Block 12 is designed to have a sliding fit between the
arms 11 and 11a, but a clearance 18 is provided between
the crotch of arms 11 and 11a and the block 12 to provide
easy installation and also to eliminate the need for close-
ly machined tolerances.

Block 12 is bifurcated by slot 19 into arms 20 and 21.
A slot 19 extends into the center of block 12 midway
between the arms 11 and 11a and substantially parallel
thereto. Block 12 is bifurcated by slot 19 into arms 20
and 21. The knife block is also provided with a knife
supporting groove 22 which is inclined to an angle with re-
spect to the crotch face representative of the desired cutting
angle. Various representative angles are indicated in
FIG. 2 and a knife 23 is illustrated in phantom at a
45° angle. The knife 23 is adjustably held in groove 22,
and by tightening the screw 13 the arms 20 and 21 are
forced toward each other by the head of screw 13 abut-
ting against arm 21 to not only hold the block 12 in position
but to also force the sides of groove 22 together to
firmly grip the knife. Lug 24 extends upwardly from
the block 12 and protrudes outside and above the crotch
of the arms 11 and 11a. Lug 24 is so positioned that
when a cutting force is placed on the knife 23 in the di-
rection of the arrow in FIG. 2 it will provide a locking
means for stopping block 12 and prevent rotation thereof.
This provides a positive locking means and maintains
block 12 always at the desired cutting angle or bevel.
(In the case of FIG. 2, 45°.)

As will be obvious from the drawings, if it is desired
to use a different bevel cut, the operator has only to re-
move screw 13 and the clamping block presently in the
machine, select a new clamping block (each of which will
be clearly marked with a representative angle), insert the
new block, and reinsert the screw 13 to lock the block
in place. This requires very little time or skill and pro-
vides an accurate cutting angle for the series of cuts to
be performed at that desired angle.

The preferred form of this invention has been described
herein, but it will be understood that changes in the de-
tails thereof may be made without departing from the
spirit of the invention, or the scope of the appended
claims.

Having thus described our invention, what we claim and
desire to protect by Letters Patent is:

1. A cutting machine comprising a knife clamping
block supporting means having two spaced substantially
parallel arms, said arms being separated by a crotch, a
bifurcated knife clamping block supported between said
arms and spaced from said crotch, means for pivotally
supporting said block, a knife clamping groove in said
block, a knife secured in said groove, and lug means ex-

tending outwardly from said block and positioned to abut a portion of said supporting means, whereby said block may be readily installed between said arms and said knife may be maintained at a fixed angle during a cutting operation by the contact of said lug means with said supporting means.

2. The cutting machine of claim 1 wherein said means for pivotally supporting said block is a screw which passes through one of said arms and said block and is threaded into the other of said arms so that said block may be 10

pressed against the other of said arms to initially hold said block in position with said lug means in contact with said supporting means.
